By Richard D.

ATTYS.

UNITED STATES PATENT OFFICE.

ERNEST E. HYATT, OF BIRKENSHAW, NEAR BRADFORD, ENGLAND.

COLOTOMY-TRUSS.

No. 838,334.

Specification of Letters Patent.

Patented Dec. 11, 1906.

Application filed January 27, 1906. Serial No. 298,211.

To all whom it may concern:

Be it known that I, ERNEST EDWARD HYATT, a subject of the King of Great Britain and Ireland, whose postal address is Mill 5 House, Birkenshaw, near Bradford, in the county of York, England, have invented certain new and useful Improvements in and Relating to Colotomy-Trusses, of which the following is a specification.

10 This invention relates to improvements in what are known as "colotomy-trusses," used in connection with the passing of excrement through the opening in the "colon," and has for its object the construction of an application 15 in such a manner that the collected excrement may be readily removed and the truss be not unsightly or prominent.

Hitherto the receptacles of trusses of this class have been constructed of either a hollow 20 pad of suitable material containing absorbent material or a hollow pad to which is attached a rubber or like receptacle, such rubber or like receptacle tending to stand out at right angles to the body, and thus become 25 very prominent, and should garments be worn over the same the bag would be bent or hang downward and the passage in the neck of same contracted or even closed by such bending, whereas by my improvement 30 these drawbacks are obviated.

In describing my invention in detail reference is made to the accompanying sheet of drawings, similar letters indicating similar parts, in which—

35 Figures 1 and 2 represent views of one form of my improved truss. Fig. 3 represents a view of the rubber bag with stiffened and threaded neck. Fig. 4 represents a view of the cap, hereinafter referred to. Figs. 5 and 6 represent views of another form of truss; and Figs. 7 and 8 represent the rubber bag and cap, respectively, for the same.

In carrying out my invention, I construct the receptacle or truss in two portions, one 45 portion A forming the pad or the like which surrounds the opening in the colon or the like, through which the excrement passes. Such portion A may be constructed of any suitable material, such as vulcanite. The 50 other portion B is a rubber bag provided with a stiffened neck C, which may screw on,

as shown in Fig. 3, or fit over an opening C' in the portion A. The opening C' projects in a downward direction (as against an outward direction hitherto used) from the truss 55 A, which takes, preferably, the shape of a partially-closed hand, as shown in Figs. 1, 2, 5, and 6, the opening C' being, as one might say, at the wrist. Should the opening C' be circular in shape, as shown in Figs. 1 and 2, 60 it is provided with a screwed neck D. The stiffened neck C of the rubber or like receptacle B, is provided with a corresponding thread D' whereby the two portions may be firmly joined together; but should the said 65 opening be oval in shape, which is the form I prefer, as such form will allow of the truss being substantially flat, then the said neck is of similar shape and a simple union joint formed between the parts. Figs. 5 and 6 70 show an oval form of neck D² in the truss, and Fig. 7 an oval form of neck C² in the receptacle B. The receptacle B is provided with a flap E, and the neck C² fits over the neck D², and the portions are held together 75 by means of a stud F on truss A, such stud passing through the buttonhole or the like F' in the flap E of receptacle B.

Should the rubber bag or the like B be removed, a cap G is provided, either circular, 80 Fig. 4, or oval, Fig. 8, depending on the nature or shape of the truss A, such cap fitting over the opening C' or D² and preventing any slight flow of excrement from escaping from the truss while the rubber bag B is being 85 emptied or cleansed. The said cap is removed when it is desired to replace the rubber or like receptacle B.

The form of truss and receptacle shown in Figs. 5, 6, and 7 is preferable to the form 90 shown in the other figures owing to the simplicity of attaching either bag B or cap G to the opening D² of the truss A. Also the component parts may be readily cleansed, as the receptacle may be turned inside out. There 95 is also less prominence.

The truss A may be so molded to fit the body that only the ordinary belt or the like is necessary to hold same in position, and the strap between the thighs is entirely done 100 away with, thus giving greater ease and comfort to the patient.

What I claim as my invention is—

A truss comprising a hollow cup-shaped pad, a depending neck on said pad, a stud on said pad, a flexible bag, a stiff neck for said bag adapted to engage the neck on said pad, and a lip on the neck of said bag adapted to engage said stud, substantially as described.

In witness whereof I have hereunto set my hand in the presence of two witnesses.

ERNEST E. HYATT.
